UNITED STATES PATENT OFFICE

2,431,960

ARMATURE FAN PULLER

Shaw O'Riley, Nashville, Tenn.

Application February 7, 1945, Serial No. 576,622

1 Claim. (Cl. 29—261)

1

The present invention relates to new and useful improvements in tools adapted for pulling fans from armatures of a type used with riveting guns and air and electric machine drills.

Such riveting guns and air and electric machine drills are equipped with fans for cooling the armature, and the fan, together with a ball-bearing assembly, is mounted on the armature shaft for rotation therewith.

After extensive use of these armatures, the fan and bearings become tight on the shaft and removal of such parts has heretofore been accomplished with considerable difficulty and labor, thereby adding to the expense of removing and repairing such parts.

It is, accordingly, an object of the present invention to provide a tool adapted for easily and quickly removing the fan and bearings from the armature shaft in a manner so as to avoid injury to the shaft as well as to the armature.

A further important object of the invention is to provide a tool of this character which may be attached to a work bench or other supporting structure within convenient reach by the workman doing the repair of the armature.

A still further object is to provide a tool of this character of simple and practical construction, strong and durable, relatively inexpensive to manufacture, and otherwise well adapted for the purposes for which the same is intended.

Other objects and advantages reside in the details of construction and operation as more fully hereinafter described and claimed, reference being had to the accompanying drawing forming part hereof, wherein like reference numerals refer to like parts throughout, and in which:

Figure 1 is a side elevational view,

Figure 2 is a similar view of another side of the tool,

Figure 3 is a top plan view with the screw and lifting arm removed,

Figure 4 is a side elevational view of one of the lifting arms,

Figure 5 is a transverse sectional view through the cross bar taken substantially on a line 5—5 of Figure 7,

Figure 6 is a sectional view taken substantially on the line 6—6 of Figure 1, and

Figure 7 is a plan view of the cross bar.

Referring now to the drawings in detail, wherein, for the purpose of illustration, I have disclosed a preferred embodiment of the invention, the numeral 5 designates a base adapted for supporting on or attaching to a bench in any suit-

2

able manner, the base having two pairs of posts 6 rising therefrom at opposite sides of the base and secured thereto by bolts 7. Each pair of posts is disposed in spaced apart relation as will be apparent from an inspection of Figure 2 of the drawing.

Also rising from the base 5 is a plurality of relatively short circularly arranged posts 8 spaced from each other and forming a cup or holder 10 adapted to receive an armature 9 in upright position within the holder. The center of the base is formed with a recess 10 adapted to receive the lower end of the shaft 11 of the armature.

To the upper end of the shaft 11 is secured the fan 12 and bearings 13, the fan being slightly spaced from the adjacent end of the armature.

The upper ends of the posts 6 are formed with vertically extending slots 14 adapted for freely receiving the laterally projecting pins or trunnions 15 formed at the opposite sides of a cross-bar 16, the pins or trunnions 15 being adapted for vertical movement in the slots.

The outer ends of the bar 16 are bifurcated as indicated at 17, and within which is received 25 the reduced upper end 18 of a lifting arm 19, one of the arms being pivotally mounted at each end of the bar 16 by means of the screws 20.

The arms 19 are of substantially L-shaped formation with the vertical portions of the arms 30 extending downwardly outside of each of the pairs of posts 6 and the horizontal portions of the arms projecting inwardly between each pair of the posts and having shallow notches 21 formed at their inner ends for bearing against the shaft 11 under the fan 12, as will be apparent 35 from an inspection of Figure 1 of the drawing.

The cross-bar 16 is formed with a central threaded opening 22 adapted for threadedly receiving a screw 23 having its lower end tapered 40 and received in a recess in the upper end of the shaft 11.

The upper end of the screw 23 is formed with a head 24 having an opening extending horizontally therethrough for slidably receiving a manually operated bar 25.

In the operation of the device with the lower ends of the lifting arms 19 positioned under the fan 12 in the manner as indicated in Figure 1 of the drawing, the rotation of the screw 23 in a 50 direction to move the cross-bar 16 upwardly will exert a pulling force on the arms 19 whereby to lift the fan 12 and slide the same off of the upper end of the shaft 11.

At the same time the armature 9 and shaft 11 55 are firmly held in an upright position within the

cup or holder formed by the posts 8 so as to prevent tilting of the armature during the pulling action and thus permit uniform lifting force to be exerted on the underside of the fan by the arms 19.

It is believed that the details of construction and manner of use of the device will be readily understood from the foregoing without further detailed explanation.

Having thus described the invention, what I claim is:

In an armature fan puller, a base, posts arising from said base in opposed pairs with vertically slotted upper ends, a bar extending horizontally between the posts of the pairs, lateral trunnions on opposite sides of said bar slidably vertically in said slots whereby the bar is vertically movable between said posts of the pairs and guided in its vertical movement, a pair of lifting arms depending from opposite ends of said bar, said arms being L-shaped to provide lower ends extending toward each other and being pivoted at the upper ends thereof to said bar for swinging thereon whereby said lower ends are adapted to be swung toward each other to position the same under a fan on an armature shaft and against opposite

sides of the shaft, and a hand screw threaded through said bar in the center thereof to extend downwardly therefrom whereby said screw may be positioned against said armature shaft and turned to feed said bar upwardly thereon and thereby pull the fan off said shaft.

SHAW O'RILEY.
